DEVICES FOR CLEANING THE WALLS OF BOREHOLES

Albert E. Atkinson, 108 Manor Road N.,
Hinchley Wood, Esher, England

Filed Nov. 29, 1957, Ser. No. 699,556

Claims priority, application Great Britain Dec. 5, 1956
11 Claims. (Cl. 166—170)

This invention relates to devices for cleaning the walls of bore holes of the kind comprising spring wires or fingers carried upon supporting means adapted to be mounted on the outside of a bore hole casing with the fingers extending outwardly with respect thereto and being shaped and arranged so that by reciprocating or rotating the casing in the hole the springs or fingers exert a scratching action which cleans the wall by removal of caked mud and the like. It is known from my U.S. Patent No. 2,714,424 to provide a cleaning device in which the fingers are formed by bundled or stranded wires and each bundle or strand is provided with one or more encircling metal sleeves or thimbles which are suitably angled to impart a desired directional set to the wire fingers as well as clamping the individual wires firmly together. In such constructions the resilience or ability of the fingers to return to their initial position after having been deflected is restricted by the clamping action of the angled sleeves or thimbles. Also it is known from my U.S. Patent No. 2,787,328 to provide a device in which the fingers are formed from closely coiled helices of spring wire or the like having one or more inserts or cores which occupy a part only of the length of each finger whereby the fingers are maintained in the desired shape or set. With such a construction the overall flexibility of the fingers is reduced since bending can take place only between the inserts or cores. It is the object of the present invention to provide an improved form of spring finger which affords the required stiffness whilst being flexible over the whole of its effective length, will maintain a desired set or shape, and also possesses the required ability to return to its initial position and shape after having been deflected during the cleaning operation.

According to the invention a spring finger for the purpose described consists in a resilient multiple wire core within a sheath consisting of a substantially close coiled wire helix, i.e. a helix having its adjacent turns juxtaposed in mutually supporting relation to each other throughout at least the major part of its extent as herein shown, the finger being shaped or set to the desired form for mounting. The aforesaid sheath extends over at least the greater part of the length of the finger and if desired its ends may be flush with the ends of the core.

According to a further feature of the invention the fitting between the wire core and the coil sheath is such that the wires of the core are enabled to slide relatively to one another to a certain extent when the finger is deflected and such relative movement can also take place in the region or regions whether the finger is angled or set. This arrangement affords flexibility over the whole of the projecting or effective length of the fingers.

According to a further feature of the invention the wire coil sheath is formed from resilient wire such as steel piano wire or tempered spring wire so that it constitutes a helical spring. In this way the sheath increases the stiffness of the finger and when deflection takes place at the angled or set portions therefore the wire sheath will lengthen under strain and thereby enhance the ability of the finger to return to its original position after the deflecting force has been removed.

In the accompanying drawing,

FIGURE 1 is a side elevation, partly broken away, of

2

a spring finger constructed in accordance with the invention;

FIGURE 2 is a sectional end elevation of FIGURE 1;

FIGURE 3 is an end view of one of the ends of the finger of FIGURE 1;

FIGURE 4 is a sectional end elevation of a modified construction of the finger;

FIGURE 4a is a detail of a modification of FIG. 4;

FIGURE 5 is an outside end elevation of another modified construction of the finger;

FIGURE 6 is a cross section on the line X—X of FIGURE 5.

In carrying the invention into effect according to one convenient mode as shown in FIGURES 1, 2 and 3, there is provided a double finger of U-shape comprising a pair of limbs 1 and 2 and a curved connecting end portion 3 which is shaped and adapted to be secured in any convenient manner to a carrier (C, FIG. 4) which can in turn be secured to a bore hole casing. The double finger is angled or set at two regions indicated at 4 and 5 in FIGURE 2, thereby providing finger portions 6 which project outwardly from the bore hole casing (not shown) and have at their ends further angled portions 7 directed either inwardly or outwardly to assist in the scraping action. It will be understood that the portion of the U-shaped double finger from the point designated 4 in FIG. 2 to the lower or recurved end of the latter, constitutes a mounting portion, whereby the scratcher element may be secured to a carrier. The double or twin finger comprises a suitable length of multiple wire core 8, the wires being laid substantially parallel and consisting of tempered spring steel wire or steel piano wire, a suitable wire size being 20 S.W.G. Preferably the wires are grouped about a center wire as shown for example in FIGURE 3 where seven wires are employed. A sheath surrounds the core 8 and consists of a close helical coil 9 of resilient wire of a gauge preferably greater than that of the core wires. This wire sheath is wound over the core wires either before or after the fingers are formed to the desired shape. The winding is so controlled that the fit between the core and the sheath will allow some relative slip or creepage of the core wires at the angled regions 4 and 5 of the finger when the latter is deflected. The wound and shaped finger is suitably tempered to afford the desired degree of resilience. The ends of the core 8 are flush with the ends of the sheath 9.

In a modified form of finger as shown in FIGURE 4, the ends of the core 8 protrude at 10 beyond the end of the sheath 9. The core ends 10 may lie parallel as illustrated or alternatively the individual core wires may be separated or splayed, as exemplified at 10a, FIG. 4a.

In a modified construction of finger as shown in FIGURES 5 and 6, the coil sheath is discontinued for a suitable distance between the angled regions 4 and 5 to expose the core at 11, leaving a relatively short length of sheath 12 extending on both sides of the angled portion or kink 5. To prevent the possibility of the sheath portion 12 turning or even being pulled off during use two or three of the intermediate coils are deformed to an oval shape as shown at 13 in FIGURES 5 and 6, thereby spreading the core wires to an elongated section.

It will be understood that twin finger elements as described above may be mounted in any convenient or desired way upon a carrier (C, FIG. 4) which is adapted to be secured to the bore hole casing. Such carrier may comprise a closed ring or may consist of separate elements preferably of channel form secured to the casing as by welding. In a convenient arrangement, the U-shaped end of the twin finger is secured by means of a cleat or cover plate C¹ suitably shaped to fit over said U-shaped end to be welded or otherwise secured to the carrier C. Preferably the fingers are mounted in such a manner that

they are inclined with respect to the longitudinal axis of the casing. Such carriers are well known in the art and are particularly illustrated in my Patent No. 2,787,328 referred to above. It will also be understood that the twin finger elements may have a narrow or a wide formation i.e. the substantially parallel finger portions may be relatively widely or closely spaced as may be desired. However, the detailed shape of the wire fingers may obviously be widely varied and the invention is not limited to the U-shaped finger construction.

It will be appreciated that spring fingers constructed in accordance with the present invention are of larger diameter than those generally employed which in many instances consist of short single wires of about .072" in diameter. In this invention the fingers may be about 1/4" in diameter and such fingers are well adapted to remove soft caked mud from the bore hole, thereby exposing the harder layers beneath to the action of the circulating fluid and permitting the progressive removal of such layers. This action is especially advantageous when cementing bore holes, and cleaning devices or scratchers according to the present invention are particularly well adapted for use in such circumstances.

I claim:

1. A well bore scratching device comprising, in combination, a carrier formed for mounting on a cylindrical casing to be run into a well bore, and a scratching finger having a mounting portion secured to said carrier and a portion projecting from said mounting portion and terminating in a free end displaced radially outwardly with respect to said formed carrier for engagement with the well bore, said finger comprising a resilient multiple wire core, said core being made up of a plurality of wires lying in generally parallel longitudinal contacting relationship, and a resilient sheath closely disposed about said core, said sheath being in the form of a helical spring having its adjacent turns juxtaposed in mutually supporting relation to each other throughout at least the major part of its extent, and said sheath loosely clasping said core wires so that said core wires are free locally to move longitudinally relative to said sheath and to each other during flexing of said finger.

2. The combination of claim 1, said core wires and resilient sheath being substantially co-terminous at their free ends.

3. The combination of claim 1, said core wires projecting beyond said resilient sheath at their free ends.

4. The combination of claim 1, said sheath and core being bent centrally of the length of said finger to constitute a U-shaped mounting portion and two free end 50

portions projecting from opposite ends of said mounting portion and lying in spaced relation to each other, said U-shaped mounting portion being secured in said carrier.

5. The combination of claim 1, said core wires being bent at an angle within said resilient sheath at a region spaced from said mounting portion.

6. The combination of claim 5, said resilient sheath including a number of coils of elliptical form embracing said core wire at said angularly bent regions.

7. A well bore wall scratcher finger having a U-shaped configuration comprising a bight and two mutually spaced legs extending in the same general direction from the respective ends of said bight, said bight constituting a mounting portion for mounting said finger upon a support for attachment to a well pipe, said finger comprising an elongated core of said U-shaped configuration made up of a plurality of generally parallel individual wires each of said configuration, and a resilient sheath closely disposed about said core, said sheath being in the form of a helical spring having its adjacent turns juxtaposed in mutually supporting relation to each other throughout at least the major part of its extent, and said sheath loosely clasping said core wires so that said core wires are free locally to move longitudinally relative to said sheath and to each other during flexing of said finger.

15 8. The combination of claim 7, said wires and sheath being substantially co-terminous at the ends thereof remote from said mounting portion.

9. The combination of claim 7, said wires projecting beyond said sheath at the ends thereof remote from said mounting portion.

10. The combination of claim 7, said wires being bent at an angle at a region within said sheath and in spaced relation to said mounting portion.

30 11. The combination of claim 10, said sheath including a number of coils of elliptical form embracing said core wires at said angularly bent region.
